[57] CLAIM

The ornamental design for an electronic learning aid housing, as shown and described.

DESCRIPTION

FIG. 1 is a top front perspective view of the electronic learning aid housing including a main housing portion and a keyboard portion showing my new ornamental design thereof;

FIG. 2 is a top front perspective view of the main housing portion thereof shown separately for clarity of illustration only;

FIG. 3 is a top plan view of the main housing portion thereof;

FIG. 4 is a bottom plan view of the main housing portion thereof;

FIG. 5 is a front elevational view of the main housing portion thereof;

FIG. 6 is a back elevational view of the main housing portion thereof;

FIG. 7 is a left side elevational view of the main housing portion thereof;

FIG. 8 is a right side elevational view of the main housing portion thereof;

FIG. 9 is a top front perspective view of the keyboard portion thereof shown separately for clarity of illustration only

FIG. 10 is a top plan view of the keyboard housing portion thereof;

FIG. 11 is a bottom plan view of the keyboard housing portion thereof;

FIG. 12 is a front elevational view of the keyboard housing portion thereof;

FIG. 13 is a back elevational view of the keyboard housing portion thereof;

FIG. 14 is a left side elevational view of the keyboard housing portion thereof; and,

FIG. 15 is a right side elevational view of the keyboard housing portion thereof;

All elements shown in broken lines are shown for illustrative purposes only and do not form part of the claimed design.
